UNITED STATES PATENT OFFICE

GEORGE SPACSINSZKI, OF NEW YORK, N. Y.

DETECTING AND SALVAGING DEVICE

Application filed March 22, 1927. Serial No. 177,247.

This invention relates to float detecting devices for vessels and more particularly to a novel yet extremely simple means for detecting and determining the position of submersible vessels particularly submarines.

One of the objects of my invention is to provide a plurality of floats in conjunction with cables and positioned on the deck of a submarine and which may be released at will so that they may float on the water surface directly above the location of the submersed vessel and thus indicate its position to other vessels operating in the same lane.

A further object of my invention is to provide a plurality of float detecting devices in connection with cables attached to suitable masts, said floats being fastened either on the deck of the vessel or within the vessel, or both, and releasable at will to afford means to signal the location in case of danger when the vessel is submersed.

To enable others skilled in the art to which the above invention relates that it may be practiced to accomplish the purposes above set forth, drawings depicting a preferred form have been annexed hereto to illustrate my invention, wherein

Fig. 1 is a plan showing the position and location of the detecting devices on the deck of a vessel.

Fig. 2 is a side view.

Fig. 3 is a sectional view showing a detail of the releasing means for the float detectors.

Referring now to the drawings wherein like reference characters designate corresponding parts throughout the several views, 5 designates the bow and 6 the stern of a conventional type of vessel of the submersible type. The said vessel is provided with a front and rear mast 7, 8, the top of which is equipped with cross bars 9 having suitable eyes 10 for the passage of a cable 10^a.

Each cable is trained about a pulley 11 located on each side of the mast and is attached to a ring 12. A float detecting buoy 13 provided with a signal such as an incandescent lamp 14 is connected by a cable 15 from a reel 16 and the end of said cable attached to the rings 12.

As shown by Fig. 3, the buoy 13 may be re-

tained on the deck of the vessel by a pivoted hook 17 passing through a loop 18 in one end of the buoy, the pivoted hook being connected to a rod 19 passing through a housing 20 within the body of the vessel. The rod 19 is provided with a spring 21 and shoulder 22 so that the hook normally retains and locks the buoy on the deck but when urged downwardly from the interior, the hook may be released from the loop and the buoy may float to the surface as the cable unwinds from the reel.

The rings 12 are so located between the masts that the location of the buoy will be directly above and substantially intermediate the bow and the stern of the vessel when submerged.

At the stern of the vessel, a second buoy 23 may be provided and also connected by a cable from a reel and leading into the interior of the vessel. The cable in this instance may be a conductor which may be utilized in connection with a suitable signal device or telegraphic key 24 whereby signals may be flashed to the incandescent lamp of the buoy 23 to indicate danger and the exact location of the vessel when submerged. The same arrangement may be provided at the bow of the vessel but for this purpose it has been deemed necessary to show the buoy construction at the stern only.

Having shown and described my invention what I now claim as new and desire to secure by Letters Patent of the U. S. is:

In combination with a submersible marine vessel, detecting means comprising a system of buoys having cables which are attached thereto at one end and to the vessel structure at the other, pivotally mounted levers on the exterior of the said vessel, down-turned hooks on the said levers and the said hooks engaging members of the said buoys and adapted to secure the same in position adjacent thereto, pull-rods passing through to the interior of the vessel and substantially at right angles to the hook elements, housings inclosing the said pull-rods and engaging the same at spaced intervals from the outer casing of the vessel, springs about the said rods and within the said housings,

and shoulders on the said rods engaging the ends of the said springs and transmitting therefrom a pressure adapted to force the said rods and the hooks thereto attached into normally closed positions.

⁵ Signed at New York in the county of New York and State of New York this 19th day of March A. D. 1927.
